UNITED STATES PATENT OFFICE.

CLYDE J. COLEMAN, OF NEW ROCHELLE, NEW YORK, ASSIGNOR, BY MESNE ASSIGNMENTS, TO STERN-COLEMAN DIAMOND MACHINE COMPANY, INC., A CORPORATION OF NEW YORK.

GEM-POLISHING.

1,168,858.

Specification of Letters Patent.

Patented Jan. 18, 1916.

Application filed November 25, 1912. Serial No. 733,419.

To all whom it may concern:

Be it known that I, CLYDE J. COLEMAN, a citizen of the United States, residing at New Rochelle, in the county of Westchester and State of New York, have invented certain new and useful Improvements Relating to Gem-Polishing, of which the following is a specification, reference being had therein to the accompanying drawings, forming part 10 thereof.

My invention relates to the art of polishing diamonds and relates more particularly to locating the grain of the diamond.

Objects of my invention are to enable the 15 finding of the grain quickly and accurately, economizing time and labor, and also eliminating to a large extent the necessity for great skill in manipulation.

It has long been known that to secure effective results in polishing a facet on a diamond, the diamond must come in contact with the polishing lap in such a position that the traveling or polishing movement of the lap on the diamond will take place in 25 the direction of the grain of the diamond at that point. Heretofore, this positioning of the diamond on the lap has been dependent upon the skill of the operator to find the position in which the most effective polishing 30 would take place, and even with the greatest of skill, sometimes several trial positionings have to be made.

My present invention includes broadly means for taking cognizance of the differences 35 in physical effects produced by different rotative positions of a diamond when the diamond is rotated on an axis perpendicular to a movable friction surface with which the diamond is held in contact. The 40 results due to the differences in physical effects produced may be immediately indicated and observed, and may also be recorded whereby the grain is indicated before any material abrasive action may have 45 taken place on the diamond by the friction surface. As examples of the different physical effects which may be utilized or taken advantage of to ascertain the grain of a diamond may be mentioned: First, by variation 50 in frictional resistance produced; second, by variation in temperature produced; third, by differences in luminous or sparkling effects; fourth, by differences in sound produced; fifth, by differences in intensity 55 of static electricity produced. In its broader

aspect the invention includes the determination of the grain by utilizing any specific physical effects such as above mentioned. More particularly the invention is directed to the utilization of the first mentioned 60 physical effect, namely, frictional resistance, and also to the illustrated means for carrying out the present invention.

Two embodiments of the present invention are illustrated in the drawings, that 65 illustrated in Figures 1, 2, 3, and 4, being adapted to both visually indicate and to record the variations in frictional resistance, produced on the friction surface of a friction member by the diamond in different 70 rotative positions of the diamond, and the other, illustrated in Fig. 5, being adapted to visually indicate, without recording, the rotative position of the diamond corresponding to the grain as desired to be ascertained 75 for polishing the diamond. In either case, the determination of the grain enables the diamond to be accurately positioned in accordance therewith on the polishing lap for effectively polishing or producing the 80 facets.

I shall now describe the grain finding machine embodying my invention illustrated in the accompanying drawings and shall thereafter point out my invention in claims. 85

Fig. 1 is a side elevation, partly in section, of a grain finder embodying my invention in one form. Fig. 2 is a detail of the electric circuit employed in the grain indicating and recording mechanism of the 90 grain finder. Fig. 3 is a plan of the grain finder. Fig. 4 is a horizontal section on a plane indicated by line 4-4 of Fig. 1, as seen from above. Fig. 5 is a side elevation of a modified construction of grain finder. 95

In the grain finder illustrated in Figs. 1 to 4, inclusive, of the drawings, a small size preliminary polishing disk or lap 1 is provided for starting the facet previously to locating the grain, that is to say, a small 100 facet or small plane surface is first formed on the generally rounded or sharp edged surface of the bruted diamond. This small facet is only of sufficient size for use in determining in which direction the grain of 105 the diamond runs in respect to this preliminary small facet. After the direction of the grain has been determined, then this knowledge is taken advantage of in positioning the diamond on the polishing lap so 110

as to finally most effectively form the complete facet. The small or preliminary lap 1 is rotatively fixed on an arbor 2, which is shown, as adapted to be directly rotated by 5 means of an electric motor 3 of which the arbor 2 forms a continuation of the armature shaft, the motor 3 being mounted on the frame of the grain finder.

The small preliminary lap 1 is surrounded 10 by the plane annular friction surface of a grain finding friction member 4. The friction member 4 is arranged concentric with the preliminary lap 1 and is rotated by the arbor 2 by means of a yielding resilient connection, shown as a coiled torsion spring 5 anchored at its upper end to the friction member 4, and at its lower end to a driving disk 6 fixed on the arbor 2.

To increase the sensitiveness of the yielding connection between the arbor 2 and the friction member 4 ball bearings are interposed, as shown in Fig. 1. The torsion spring 5 measures the frictional resistance to which the friction surface of the friction member 4 is subjected. Any change or variation 25 in friction on the friction surface of the friction member 4, will result in corresponding changes in rotative position of the friction member relatively to the arbor 2.

30 The sliding friction of a friction surface in contact with a diamond is greater in the direction of the grain of the diamond, and if the diamond be slowly rotated on an axis perpendicular to a traveling friction surface with 35 which the diamond is in sliding contact, the frictional resistance between the diamond and the friction surface will increase each time the diamond comes into a position so that the direction of the sliding movement 40 corresponds with the direction of the grain of the diamond. From the foregoing fact, it follows that if a diamond be held in contact with the plane annular friction surface of the friction member 4 and be rotated on 45 an axis perpendicular to such friction surface, the friction member 4 will periodically lag in its rotation, or rotatively shift its position in reference to the arbor 2, the periods of lagging movement corresponding 50 to the periods of frictional contact in which the sliding movement takes place in the direction of the grain of the diamond.

In carrying out my invention means are 55 provided for holding and rotating a diamond in the manner described and also means are provided for indicating and recording variations in the torque required to rotate the sensitive friction member 4. In the 60 present machine for finding the grain of diamonds the same diamond holding head is employed to hold the diamond on the preliminary lap 1, and on the friction member 4, the diamond preferably being rotated on an axis perpendicular to the preliminary lap 1, during the formation of the small

initial facet, such rotation of the diamond enabling the grain of the diamond to be taken advantage of periodically during each rotation of the diamond, for more expeditiously forming the small facet.

70 It should be here noted that the diamond holding head of the present machine, including the means for rotating a diamond relatively to a polishing lap while forming a facet, means for adjusting the diamond 75 about its geometric center, and also other features, is made the subject of a separate application for patent filed on even date herewith, Serial Number 733,417, and the cooling means herein disclosed is made the 80 subject of another patent application, filed July 20th, 1912, Serial Number 710,623, for "Means for holding diamonds during abrasive treatment."

85 The diamond holding head will now be sufficiently described for the purposes of the present invention. The holder head for the diamond has a vertical main shaft 7, journaled for rotation and also for free limited vertical movement in a journal block 8, 90 adjustably and removably mounted on a horizontal upper arm 9 of the machine frame. The journal block 8 is held in place on the supporting arm 9 by a clamp bar 10, controlled by a wing nut 11. An arcuate arm 12 is adjustably carried by the lower end of the supporting shaft 7, and provides for the adjustment of the diamond about its geometric center for forming the facets, in 95 the different concentric rows of facets at one side of the girdle. A dop holder 13 is carried by one end of the arcuate arm 12 and supports a drop having a head 14 and a supporting stem 15. The dop is rotatively adjustable about its stem 15 to provide for 100 forming the different facets concentrically around the diamond. A bruted diamond 16 is shown as held by the dop head 14 in axial alignment with the supporting shaft 7. The diamond 16 may be held on a usual arbor 105 inserted in the dop head 14, and the diamond may be held in place on the arbor by ordinary "diamond cutters cement" or by any suitable wax like material, melting of the fusible adhesive being prevented by the 110 cooling means as indicated by the conduits 17 and 18 for supplying a cooling fluid, the conduit 18 being flexible to permit adjustment of the arcuate arm 12.

115 The diamond 16 is shown in the drawings as presented to the preliminary lap 1 for forming an initial facet on the diamond. To present the diamond 16 to the friction surface of the friction member 4 for determining or locating the grain of the diamond, the clamp 10 is released and the journal block 8 is slipped along the supporting arm 9 to the proper place and the clamp 10 again tightened. The vertical shaft 7 and the 120 parts carried thereby, including the dia-

mond 16, may be rotated by means of a worm wheel 19 fixed on the shaft 7, and engaged by a worm 20 carried by a counter shaft 21 journaled in the frame of the machine. It is to be noted that the worm 20 is of sufficient length to engage the gear 19 in either of the positions of lateral adjustment of the diamond holding head above mentioned. The counter shaft 21 is adapted to be rotated by an electric motor 22, connected to the counter shaft 21 by means of a worm 23 fixed on the armature shaft of the motor and meshing with a worm gear 24 fixed on the counter shaft. By means of the speed reductions from the two sets of worm gears, a comparatively slow speed of rotation will be given to the vertical shaft 7 which directly rotates the diamond 16.

The means provided for indicating and recording the variations in the torque required to drive the sensitive friction member 4 in the different rotative positions of the diamond 16 will now be described. The disk 6, which carries the lower end of the torsion spring 5, is composed of insulating material, as indicated in Fig. 1, and a split graphite resistance ring 25 is carried by the disk 6 on its upper side. A contact brush 26 is coöperative with the resistance ring 25 and is carried by the lower end of a sleeve portion of the friction member 4, this sleeve portion being shown as surrounded by the coiled torsion spring 5. A stop pin 27 (Fig. 4) is provided on the disk 6 for the brush 26, this stop pin being located at a point so that the brush 26 will make contact with the resistance ring 25 just at one side of the split or division in such ring, and so that as the spring is put under tension by the driving torque applied to the friction member 4, the brush 26 will travel around the resistance ring 25 in a direction away from the division or split therein. One end of the resistance ring 25 is electrically connected through a conductor 28 with a contact ring 29 which is insulated from the arbor 2 by an insulating sleeve 30 (Fig. 2). A brush 31 coöperates with the insulating ring 29 and a conductor 32 connects this brush with a battery 33. The electric circuit is adapted to be completed from the battery 33 through a conductor 34, through the coil of an electrical measuring instrument 35, a conductor 36, a circuit closer 37, a conductor 38, a brush 39, and a grounded contact ring 40 which is carried by and is in electrical connection with the arbor 2.

From the preceding explanation of the construction, it will be understood that any movement of the friction member 4 relatively to the arbor 2 will cause the contact brush 26 to travel over the resistance ring 25 and will accordingly vary the resistance included in the electric circuit in which is included the electrical measuring instrument

35, and will cause rotative movement of the pivoted armature coil of such instrument. This coil is shown as mechanically connected by means of a crank 41 and a link 42 with a marker 43. The marker 43 is coöperative with a dial 44, rotatively carried by the upper end of the vertical shaft 7 of the diamond holding head.

In the operation of the grain finding machine, the diamond is first applied to the rapidly rotating preliminary lap 1, as shown in Fig. 1, and, for effective operation in forming a preliminary facet, the diamond is slowly rotated on an axis perpendicular to the lap 1, by means of the electric motor 22, the diamond being pressed against the abrasive surface of the lap by reason of the weight of the diamond holding head. When the preliminary facet has been formed, the diamond holding head is shifted along the supporting arm 9 to bring the diamond into contact with the friction surface of the sensitive friction member 4, upon the friction surface of which the diamond will be held with a uniform pressure. This shifting of the diamond holding head also brings the dial 44 into coöperative relationship with the marker 43. The diamond holding head will now slowly rotate the diamond in contact with the rapidly moving annular friction surface of the friction member 4. The torque required to rotate the friction member 4 will be measured by the torsion spring 5, and as the torque varies, due to the different rotative positions of the diamond in reference to its grain, the brush 26, moving over the resistance ring 25, will vary the resistance included in the circuit with the electrical measuring instrument 35, and will cause the marker 43 to be actuated to produce a record on the dial 44. Because of the fact that the dial 44 rotates in unity with the diamond, the record made on the dial will directly indicate the grain of the diamond and may be used as a guide in placing the diamond on the polishing lap. When the grain for any particular facet has been located, the entire diamond holding head, including the removable journal block 8, may be removed from the grain finding machine and transferred to a suitable diamond polishing machine, with the diamond in correct position as to its grain in reference to the polishing movement of the polishing lap for producing the complete facet. The operation is repeated for each facet. The friction surface of the friction member 4 may be of iron surfaced with diamond dust similar to that of a polishing lap.

The modified construction illustrated in Fig. 5 embodies a simplified form of the invention. In this construction a small polishing lap 45 is adapted to be rotated by a light power series wound electric motor 46

which is very delicately responsive to load variations. The circuit of this motor includes a current meter 47 included in the circuit in series. When, as in the first instance, a diamond in contact with the rapidly rotating lap 45 is slowly rotated on a vertical axis, as indicated by a worm gear 48, the variations in load on the motor 46, caused by the varying angles of presentation of the grain of the diamond to the polishing movement of the lap 45 will be visually indicated by the ammeter 47. The indications of the ammeter in the different rotative positions of the diamond will enable the diamond-carrying holder head to be lifted from the grain finding machine and correctly positioned on a polishing lap.

It is obvious that various modifications may be made in the constructions shown in the drawings and above particularly described, within the principle and scope of my invention.

I claim:

1. A machine for locating the grain of a diamond comprising a friction surface, means for holding a diamond in contact with such surface, means for producing relative traveling movement between the friction surface and diamond in the plane of the friction surface at its point of contact with the diamond, and means for taking cognizance of differences in physical effects produced in the different rotative positions of the diamond when rotated about an axis perpendicular to said friction surface.

2. An arrangement of the class described having in combination a relatively movable friction surface, means for rotating the facet of a gem upon said surface, and indicating mechanism immediately responsive to differences in the physical effects produced as the facet is rotated, substantially for the purpose specified.

3. A machine for locating the grain of a diamond comprising a friction surface, means for holding a diamond in contact with such surface, means for producing relative traveling movement between the friction surface and diamond in the plane of the friction surface at its point of contact with the diamond, means for producing relative rotation between the diamond and friction surface about an axis perpendicular to the friction surface at the point of contact of the diamond therewith, and means for measuring the frictional resistance produced between the diamond and the friction surface by the traveling movement while the rotary movement is also taking place.

4. A machine for locating the grain of a diamond, comprising a rotative friction member provided with a friction surface, means for holding the diamond in frictional contact with the friction surface at an eccentric point on the friction member, means

for rotating the friction member, means for rotating the diamond on an axis perpendicular to the friction surface at the point of contact of the diamond therewith, and means for indicating the torque required to rotate the friction member in the different rotative positions of the diamond relative to the friction member.

5. In an apparatus of the class described, means for holding a diamond, a suitable surface in engagement therewith, means for moving said surface relatively to the diamond, and means for taking cognizance of differences in physical effect produced with the diamond in different rotative positions about an axis perpendicular to said surface.

6. A machine for locating the grain of a diamond comprising a rotative friction member provided with a friction surface, means for holding the diamond in frictional contact with the friction surface at an eccentric point on the friction member, means for rotating the friction member, means for rotating the diamond on an axis perpendicular to the friction surface at the point of contact of the diamond therewith, resilient means connected between the means for rotating the friction member and such member for permitting the friction member to rotatively yield relative to its rotating means, and electrical means for indicating the extent of yielding in the resilient means corresponding to different rotative positions of the diamond relative to the friction member.

7. A machine for locating the grain of a diamond comprising a rotative friction member provided with a plane friction surface, driving means for rotating the friction member, a torsion spring interposed in the driving connections between the driving means and the friction member for permitting the friction member to rotatively yield relative to the driving means, a variable resistance rotatively carried by the driving means, a movable contact member rotatively carried by the friction member and engaging the variable resistance, an electric circuit including the movable contact member and the variable resistance, a source of electric current included in the circuit, an electrical measuring instrument included in the circuit, means for holding a diamond in contact with the friction surface of the friction member, and means for rotating the diamond on an axis perpendicular to the friction surface, whereby the electrical measuring instrument will indicate the driving torque of the friction member in different rotative positions of the diamond on the friction member and will thereby determine the grain of the diamond.

8. A machine for locating the grain of a diamond comprising a rotative friction member provided with a friction surface,

- means for holding the diamond in contact with the friction surface, means for rotating the diamond on an axis perpendicular to the friction surface at the point of contact of the diamond therewith, driving means for rotating the friction member, resilient means connected between the driving means and the friction member for permitting the friction member to rotatively shift relatively 5 to the driving means therefor, a record blank arranged to be moved in harmony with the rotation of the diamond, a marker coöoperative with the record blank, and mechanism for communicating the rotary 10 shifting movement of the friction member relatively to its driving means to the marker for recording on the record blank the varying amounts of friction between the diamond and the friction member in different 15 rotary positions of the diamond relative to the friction member.
9. A machine for locating the grain of a diamond comprising a rotative friction member with a plane friction surface, means 20 for holding the diamond in contact with the friction surface, means for rotating the diamond on an axis perpendicular to the friction surface, a dial mounted to rotate with the diamond, driving means for rotating the friction member, a torsion spring interposed in the driving connections between the driving 25 means and friction member for permitting the friction member to rotatively shift relatively to the driving means, a split resistance ring rotatively carried by the driving means, a contact brush rotatively carried by the friction member and engaging the resistance ring, an electric circuit including the contact brush and the resistance ring, a source 30 of electric current included in the circuit, an 35 electrical measuring instrument also included in the circuit and having a pivoted indicating shaft, and a marker actuated by the indicating shaft and coöoperating with the dial. 40
10. A grain finding machine for locating the grain of a diamond comprising a polishing lap, an arbor on which the lap is fixed for rotation with the arbor, driving means for rotating the arbor, a rotative friction member mounted for rotative movement on the arbor and having an annular friction surface concentric with the lap, resilient rotatively yielding driving connections between the arbor and the friction 45 member, a rotative dop holder for holding the diamond, the dop holder and the arbor being relatively adjustable so that the dop holder will hold the diamond in contact with the friction member or with the lap according to the relative adjustment of the dop holder and the arbor, means for rotating the dop holder so as to rotate the diamond on an axis perpendicular to the friction surface of the friction member, a dial 50 rotative with the dop holder, a marker coöoperative with the dial, and mechanism for transmitting the rotation of the friction member relatively to the arbor to the marker, whereby variations in friction of 55 the diamond with the friction member for different rotative positions of the diamond will be recorded on the dial. 60
- In testimony whereof I have affixed my signature in presence of two witnesses.
- CLYDE J. COLEMAN.
